DEVICE FOR SHARPENING HYPODERMIC
NEEDLES AND OTHER INSTRUMENTS

George W. Jacoby, Jr., Wooster, Ohio

Application November 30, 1949, Serial No. 130,304

1 Claim. (Cl. 51—92)

1

This invention relates to the sharpening of medical and surgical instruments, and is embodied in a machine to facilitate the sharpening of hypodermic needles of various types, and of knives, scalpels, scissors, and other surgical instruments. The preferred embodiment of the invention incorporates apparatus described in my Patent No. 2,565,309, dated August 21, 1951, for Hypodermic Needle Sharpener. The present invention involves certain additions and improvements to the invention described in said patent which will be particularly described.

The apparatus disclosed in said patent is particularly adapted for the pointing and refacing of hypodermic needles with concave faces. The present invention includes a gaging device by which this operation may be performed with greater celerity, uniformity, and precision. A commercial embodiment of the invention disclosed in said patent has been most favorably received. However, although the instrument is highly successful, it is essentially a specialized single-purpose machine. This invention involves the elaboration of the machine so that the basic machine may be used for sharpening hypodermic needles with flat faces and also for sharpening surgical instruments. One of the great merits of this invention is that the additional structure by which the machine is made a versatile general purpose device for use by hospitals and clinics is that the additional structure does not lessen the usefulness of the machine for its original function and does not involve any substantial complication of the machine or significant increase in the cost. It is thus possible, by virtue of the invention, to provide an extremely useful general-purpose machine which greatly facilitates the sharpening of surgical instruments of various sorts and makes possible the accomplishment of satisfactory sharpening by persons of no great skill.

The principal object of the invention is to facilitate the sharpening of hypodermic needles of various types and various edged tools of the surgeon and to provide a machine for this purpose. Subsidiary objects are to improve the precision of hypodermic needle sharpening, to provide for the sharpening of flat-faced needles, to provide a stropping or honing element, to provide an abrasive element particularly suited to knives and the like, and to provide a guiding member to insure the correct beveling of scissors and similar instruments. A further object of the invention is to provide a slightly flexible abrasive disk which is particularly suited to the sharpening of knives,

chisels, scissors, and the like and which is economical to manufacture.

The manner in which the various objects are realized and the advantages of the invention will be better understood by reference to the detailed description of the preferred embodiment of the invention and the accompanying drawings. Fig. 1 is an axonometric view of a sharpening device in accordance with the invention; Fig. 2 is a plan view of the same; Fig. 3 is a vertical sectional view; Fig. 4 is a partial plan view illustrating the method of sharpening scissors; Fig. 5 is a view of a head for holding needles to grind a straight bevel or flat face; Fig. 6 is a transverse sectional view of an abrasive disk according to the invention; and Fig. 7 is a partial view illustrating the honing element.

The apparatus comprises a base 11 preferably supported on rubber feet 12. A small motor 13, which may be of a type commonly used for driving small apparatus, is mounted on the base by uprights 14 bolted to the base, the uprights supporting the motor through resilient fittings of a type known in the art coupled to the ends of the motor frame. The brackets are fixed to the frame by bolts 16. The motor may be provided with a cord and switch (not shown) in any conventional manner. The motor shaft is extended to form a spindle or arbor 18 on which a sharpening element comprising a grinding cylinder 19 and a polishing cylinder 21 is mounted. The cylinders 19 and 21 may comprise a rubber core 20 covered with cylinders of abrasive paper which are retained by axial compression of the rubber, and are identical except that the cylinder 19 is coated with a coarser abrasive than the cylinder 21. The abrasive on the grinding wheel 19 is of a fine grade such as 280 to 340 grit and the wheel 21 is coated with an extremely fine abrasive, 500 grit or finer, to perform a smoothing and polishing operation after the grinding. The cylinders are retained by axial compression against a shoulder at the end of the shaft 18 by a nut 22 threaded on the outer end of the shaft. The shaft turns clockwise as viewed in Fig. 1.

The apparatus includes means for clamping the shaft of the needle N and reciprocating it over the abrading element, this means comprising a reciprocable carriage incorporating mechanisms for adjusting the relation of the needle to the abrasive stones to secure the proper angle or bevel of the point of the needle and means for feeding the needle into engagement with the stone. Obviously, an arrangement for this purpose may be widely varied in structure. A form of apparatus

which is simple in structure and light in weight which has been devised for the purpose comprises two uprights 26 and 27 fixed to the base and bored to receive two rods 28 and 29 slidable in the uprights. A support 31 fixed to the rod 28 by a setscrew 32 is pivoted by a pin 33 to a clevised adjusting member 34 formed with a clearance slot 35 for the rod 29. An adjusting screw 36 passes through a transverse bore in the rod 29 and is formed with a shoulder 37 bearing against the rod. The portion of the screw 36 beyond the shoulder is unthreaded and extends into a bore 38 in the member 34. A coil spring 39 urges the member 34 upwardly, but, as will be apparent, it may be moved downwardly by adjustment of the screw 36 or by pressure on the member 34. The spring 39 allows for depression of the needle against the abrasive by manual force thereon.

A needle slide 41 is mounted on the support 31 to slide toward and away from the abrading element, being formed with a groove 42 on its under surface which receives the support 31. A feed screw 43 is threaded in the end of the support 31 and is formed with an unthreaded portion passing through an opening 44 in the slide 41. A pinch collar 45 is fixed on the feed screw 43 abutting the end portion of the slide 41 so that the feed screw 43 is rotatable in the slide 41 but incapable of axial movement relative thereto; so that rotation of the screw 43 moves the slide 41 toward or away from the abrading element. A pin 47 fixed in the inner end of the slide 41 is received in a bore 48 in the support 31 to retain the slide 41 in engagement with the support 31.

Means are provided on the inner end of the slide 41 to clamp or hold a hypodermic needle during the sharpening operation. While this structure may take various forms, it is desirable that it accommodate needles of various gages and lengths and hold them positively. Of course, no substantial force is involved in this light abrading operation, but the angular relation of the needle to the cylinders 19 and 21 and the pressure thereon should be capable of accurate control. Also, it is highly desirable for precise work that the needle be held near its point. A feature of the machine lies in the provision of means whereby the needle may be rotated about its own axis to bevel the face produced by the sharpening and thereby create a razor edge. In the form illustrated, the needle holder comprises a small block 51 retained against the end face of the slide 41 by a shouldered screw 52 which serves as a pivot for the block. The needle N is inserted through an aperture 54 in the block which is parallel to the pivot of the block and formed with a V bottom, and is clamped therein by a screw 56 threaded into the upper end of the block. The bore 54 is large enough to accommodate needles of large size. The block is formed with lateral flanges 57 which embrace the end of the slide 41 but are spaced slightly therefrom so that the block 51 may be rotated preferably some ten degrees to each side of its normal upright position.

The structure above described corresponds to that disclosed in my above-mentioned patent.

The present invention includes means by which the needle may be accurately set in the clamping block 51 so that a group of needles may be ground with the same angle or degree of sharpness of the point. The gaging device by which this result is obtained comprises a stud 61 fixed to and extending from the forward motor bracket

14 and a thumb screw 62 threaded through the stud 61. The manner in which this gage is used is illustrated in Fig. 3. Hypodermic needles usually are formed with a flat face on the butt which is in alignment circumferentially of the axis of the needle with the ground face of the needle, which face may be exposed to the abrasive wheel by resting the butt of the needle against the upper surface of the slide 41 to which the needle is clamped. The thumb screw 56 may be adjusted so that when the needle is inserted into the opening 54 in the clamping block, the point of the needle engages the thumb screw 62. The location of the end of the needle is thus determined by its engagement with the screw 62 and the needle is then clamped by the thumb screw 56. To perform the refacing operation the slide 41 and support 31 are rotated slightly about the rod 28, as indicated by the broken lines in Fig. 3, to bring the needle into engagement with the abrading cylinder 19. As will be apparent, the angle of the ground face of the needle with respect to the longitudinal axis of the needle may be varied by adjustment of the thumb screw 62 to determine the zone of engagement of the end of the needle with the abrasive. Thus, by virtue of the gauge, a group of needles of the same or approximately the same size may be ground to the same desired degree of acuteness of the point and much more accurate results may be obtained than by merely relying on the skill of the operator to locate the needle correctly.

Once the needle has been properly located and clamped it is refaced and polished by the wheels 19 and 21, the needle being shifted longitudinally of the wheels by the operator while it is held in engagement therewith by the depression of the needle holder. The preferred technique of sharpening needles need not be further described herein, since it is described in detail in the aforesaid patent.

As will be apparent, the cylindrical abrasive forms a concave face on the needle which is preferred for many uses of hypodermic needles. However, needles formed with a flat or straight bevel face are also employed, and the present invention provides for forming or sharpening needle points of hypodermic needles with such faces. This is accomplished by an abrasive disk 63 fixed on the shaft of the machine and a head for holding the needles in correct position for engagement with the disk. The abrasive disk 63 is mounted on the shaft 18 abutting the outer end of the polishing cylinder 21. The preferred structure of the abrasive disk is shown more clearly in Fig. 6. It comprises a disk 64 of light sheet metal formed with a hole 66 to fit over the shaft. Disks 67 and 68 of paper or cloth coated with abrasive and formed with central openings 69 for the shaft are cemented to the face of the disk 64. The disk 64 is preferably about one and three-quarters inches in diameter and the abrasive disks are of sufficient size to extend approximately a quarter of an inch beyond the metal disk. The portions of the abrasive disks which extend beyond the metal are cemented to each other. The assembly thus provides an abrasive disk the center portion of which is slightly flexible because of the resiliency of the metal and the outer portion of which is much more flexible. The central portion is substantially rigid under the small forces involved in refacing needles. It will be appreciated, however, that the circumferential portion is far

stiffer than a single sheet of abrasive coated paper since the two sheets cemented together are relatively stiff. The flexible outer edge of the abrasive disk makes it much more suitable for operation on curved edges.

The needles are held and guided for formation of the straight bevel point by a head 70 (Figs. 2 and 5) adapted for mounting on the needle slide 41. This head 70 is preferably in the form of a block with a slot 71 in the lower surface dimensioned to straddle the needle slide 41 and with a clamping screw 72 threaded in one leg of the block. When it is desired to sharpen straight pointed needles the block 70 is fitted over the slide 41 in the approximate position indicated by Fig. 2, and retained thereon by tightening the clamping screw 72. A needle clamping screw 73 is threaded into the central part of the block and passes through a hole in a jaw 74 which rests on the block 70. The jaw 74 is formed with a rib 75 which rides in a slot 76 in the upper face of the block 70. The jaw 74 extends beyond the left end of the block 70 so that the end portion 77 of the jaw may be depressed to insert a needle under the other end. The upper face of the block 70 is formed with a plurality of radiating grooves 78 at various angles to the plane of the abrasive disk 63. The needles may be laid in any one of the grooves 78 to determine accurately any one of several angles of beveling of the point, and is retained by tightening the thumb screw 73. After the needle is clamped, it may be brought into engagement with the rigid central part of the abrasive disk by sliding the carriage and may be traversed over the surface of the disk by rotating the carriage or holder about the rod 28. The block 70 may be removed when not in use, or may be slid toward the outer end of the slide 41 so as not to interfere with other operations.

The abrasive disk 63 is not only useful for sharpening needles, but may also be used for sharpening knives, scissors, and other instruments. The disks are preferably covered with a fine abrasive and are therefore not especially adapted for rough sharpening jobs, but are particularly suited for producing a fine edge on a slightly dulled instrument. The disk 63 may be used for sharpening knives, scalpels, and such by merely holding the device to be sharpened against the face of the disk at the proper angle to produce the desired edge. Ordinarily, no great difficulty is experienced in sharpening devices of this sort freehand.

Scissors, however, often prove troublesome to sharpen for those who are not expert, and for this reason I have provided a conical sleeve 81 by means of which the edge of the scissor blade may be exposed to the disk at a constant and suitable angle. In its preferred form the sleeve or guide for scissor sharpening is a frusto-conical element 81 formed with a central hole to fit over the threaded end of the shaft 18 and slightly larger than the nut 22. The angle of the cone may vary over a range from about three degrees to about fifteen degrees to the axis of the shaft, and cones of various angles may be supplied to suit various needs. An angle of ten degrees, which is a median value, is illustrated. As illustrated in Fig. 4, the edge of the scissor blade S is pressed against the disk 63 with the inside face of the blade bearing on the smooth cone 81. The blade may then be moved longitudinally thereof to grind or sharpen from one end to the other, and a constant angle is easily maintained.

The blade is held slightly spaced from the central portion of the disk and bearing against the flexible edge portion at one side so that the grinding movement of the abrasive over the surface being ground is in one direction only, which provides a better edge. The shaft turns clockwise as viewed from the end. It is preferable to engage the blade with the downwardly moving edge of the wheel.

Fig. 7 illustrates a stropping element which is provided for eliminating the small roughness which remains after the abrading operation. The stropping element 90, which may be mounted on the shaft in place of the conical guide member 81 with or without removing the abrasive disk 63, comprises three leather disks 92 formed with central openings for mounting on the shaft. The central portions of the disks are compressed together lightly by the nut 22, and washer 93, if desired, and the disks are thus driven frictionally. When a knife or other blade has been sharpened, the ragged edge may be removed by the rubbing action of the edges of the leather disk.

The disks are particularly useful in removing ragged edges from the refaced needles. As will be noted, the inner edges of the outer disks and both edges of the central disk are slightly beveled to form grooves 83 which are adapted to receive the shaft or end of the needle. The grooves, which may be provided by filing the disks or in any other suitable manner, greatly facilitate the stropping of needles since it has been found that with a plain cylindrical element the needles tend to be thrown off the disk because of the engagement of the sharp edges of the needle faces with the leather. As illustrated in Fig. 7, the end portion 85 of the needle may be laid in the groove to prevent this. Since the leather disks are resilient and may be spread apart, the shaft of the needle may be pushed between the rotating disks and rotated about its own axis as it is drawn longitudinally of the shaft between the disks so as to clean and polish the shaft of the needle.

Normally, when the instrument is used for hypodermic needles, the disks 92 will be mounted on the shaft, but they may be easily removed and replaced by the conical element 81 when scissors are to be sharpened.

It will be seen from the foregoing that the invention provides an extremely versatile, flexible, and convenient instrument for sharpening hypodermic needles and various edged tools such as are used in surgery. It will be apparent to those skilled in the art that many variations of form may be devised within the scope of the invention, which is not to be regarded as restricted by the description herein of the preferred embodiment of the invention.

I claim:

A device for sharpening hypodermic needles comprising in combination a rotatable cylindrical abrasive element, power means for rotating said abrasive element, a needle support, means on the support for releasably clamping a needle to engage the periphery of the abrasive element to form a face on the needle shaft, mechanism for positioning the clamping means and a needle relative to the abrasive element, a mounting, and a gauge threaded in said mounting for adjustment in a path normal to a radial plane through the centerline of the abrasive element whereby the extreme end of the needle may be positioned along the periphery of said abrasive element and the position of the clamping means established

before the needle is engaged with the abrasive element.

GEORGE W. JACOBY, Jr.
